UNITED STATES PATENT OFFICE.

MAX SKOLNIK, OF MINNEAPOLIS, MINNESOTA, ASSIGNOR TO THE SKOLNIK PATENTS,
INCORPORATED, OF MINNEAPOLIS, MINNESOTA, A CORPORATION OF INDIANA.

POWER PLANE.

Application filed July 20, 1925. Serial No. 44,721.

My invention relates to power planes, and an object is to provide a plane by means of which the surface of wood may be smoothed with the expenditure of but little effort on 5 the part of the operator. I accomplish the objects of my invention by the provision of a support which carries a plurality of vertical shafts driven by an electric motor and having cutters secured to their lower ends in 10 overlapping relation so that the wood may be smoothly planed by the rotation of the cutters.

The full objects and advantages of my invention will appear in connection with the 15 detailed description thereof and the novel features embodied in my inventive idea will be particularly pointed out in the claims.

In the accompanying drawings which illustrate a practical embodiment of my invention, Fig. 1 is a side elevational view of the device. Fig. 2 is a view mostly in vertical, longitudinal section. Fig. 3 is a bottom plan view. Fig. 4 is a view in horizontal section on the line 4—4 of Fig. 2. Fig. 25 5 is a view showing a board partly planed.

As shown in the drawings the device includes two bottom or base members 10 and 12 which are spaced from each other. The member 10 is provided with an upwardly extending handle member 14 at its outer end and with an upwardly extending flange 16 at its inner end. The member 12 is provided with an upwardly extending flange 18 at its inner end, the upper end of this flange 35 being connected by a curved arm 20 with the outer end of the member 12. A casting 22 is placed between the flanges 16 and 18. This casting has a projection 24 on one side which cooperates slidably with a recess in the flange 16 while on the other side the casting 40 has a dove-tail projection 26 which cooperates slidably with a corresponding recess in the flange 18 as shown in Fig. 4. The flange 16 is provided with a vertical slot 28 thru which a bolt 30 secured to the casting 22 extends, the outer end of this bolt being provided with a nut 32. The flange 18 is provided with a vertical slot 34 thru which a screw 36 extends, the inner end of the screw 50 engaging a threaded hole in the casting and the outer end of the screw having a knurled head 38. The casting on one side has a lug 40 provided with a screw-threaded hole for

receiving a set screw 42 which engages the upper end of the flange 16. On the other side 55 the casting has a lug 44 in which is rotatably mounted a screw 46 whose lower end engages a screw threaded opening at the upper end of the flange 18 and whose upper end is provided with a knurled head 48. The upper portion of the casting 22 is formed as a 60 socket member which receives an electric motor 52 having a shaft 54. Current is supplied to the motor from any convenient source of electric supply by means of wires 65 55 and 56. The wire 55 connects the motor directly with the source of supply while the wire 56 connects the motor with a contact member 58 mounted on an insulating disk 60 placed in a recess in the upper end of the 70 handle member 14. A second contact member 62 is spaced from the contact member 58 and is connected by a wire 64 with the source of electric supply. A cover plate 66 is held over the recess by a screw 68. A 75 bridge member 70 is secured to the lower end of a plunger rod 72 passing thru the cover plate and normally held upwardly by a coiled spring 74. The circuit is completed 80 when the rod 72 is depressed. The lower end of the motor shaft 54 is mounted in a partition member 76 extending across the casting 22 and above this partition member the shaft has secured thereto a gear 78 meshing with a plurality of gears 80 arranged concentrically around the same. In the embodiment 85 shown there are four of the gears 80 but it will be understood that any suitable number may be employed. These gears are secured to shafts 82 rotatably mounted in bearings 90 carried by the partition 76 and by a disk 84 secured to the bottom of the casting 22 by screws 86. The lower ends of the shafts 82 are provided with internally screw threaded 95 sockets 88 which receive the externally screw threaded shanks of cutters 90 which project below the under surface of the bottom member 12 and whose lower ends are intended to come flush with the under surface of the bottom member 10. In other words the lower surface of the member 10 is disposed below the lower surface of the member 12 by the amount of cut. A gauge plate 92 is secured to the outer ends of two rods 94 and 96. The rod 94 extends thru an opening in the member 10 and is adjustably held by a set screw 100

105

98. The rod 96 extends thru an opening in the member 12 and is adjustably held by a set screw 100.

The operation and advantages of my invention will now be obvious. The cutters will be caused to rotate when the plunger rod 72 is depressed so that current is conducted to the motor. While the drawings show all of the cutters as being the same, 10 it will be understood that one or more of them may be made longer or of different shape so as to produce a deeper cut as for instance in making moldings. When they are all alike a smooth planed surface will 15 be produced on the board B. By referring to Fig. 3 it will be seen that the cutters overlap so that no ridges are left in the planed surface. Fig. 5 shows a cut C made adjacent the edge of the board B. Successive 20 cuts may be made to produce a planed surface on the board by adjusting the gauge plate 92. If desired one or more cuts may be made in spaced relation to other cuts as indicated at C' so as to leave raised portions 25 or ribs R on the board. The depth of cut may be regulated by adjusting the attachment of the flange 18 to the casting. When different lengths of cutters are used it will be understood that the flange 16 may be ad- 30 justed on the casting so as to maintain the lower surface of the member 10 flush with the outer ends of the cutters. The device is moved along the material being operated

upon by the operator who grasps the handle 14 and the curved arm 20 and closes the 35 switch to cause the cutters to rotate.

I claim:

1. A power plane comprising a support, an electric motor mounted on said support, a cutting device carried by said support and driven by said motor, a vertically adjustable base member mounted at one side of said support resting upon the unplaned material, and a second vertically adjustable base member mounted at the opposite side of said support with its lower surface at a lower level than that of said first base member for resting upon the planed material. 40 45

2. A power plane comprising a hollow casting, having a partition between the ends thereof, two base members supported for vertical adjustment at the opposite sides of said casting for resting upon the material being planed, an electric motor mounted on the upper end of said casting, said motor 50 having a vertical shaft rotatably mounted in said partition, a disk secured to the bottom of said casting, a plurality of vertical shafts rotatably mounted in said disk and in said partition, gearing connecting said 55 motor shaft and said plurality of shafts, and cutters secured to the lower ends of said last mentioned shafts. 60

In testimony whereof I hereunto affix my signature.

MAX SKOLNIK.
